United States Patent Office

Des. 228,893
Patented Oct. 30, 1973

228,893

BIN CONSTRUCTION

Rodney D. Jacobson, Ray, N. Dak., assignor to Jacobson and Sons Construction Co., Inc.

Filed Nov. 20, 1970, Ser. No. 26,241

Term of patent 14 years

The portion of the term of the patent subsequent to July 21, 1984, has been disclaimed

Int. Cl. D25—03

U.S. Cl. D13—1 R

The sole figure is a view in perspective as seen from the bottom, end and one side showing my new design for a bin construction, the end and side opposite that shown being substantially a mirror image.

I claim:

The ornamental design for a bin construction, as shown and described.
